UNITED STATES PATENT OFFICE.

EDWARD G. PARKHURST, OF HARTFORD, CONNECTICUT.

DESIGN FOR A CARTRIDGE-CLIP RECEIVER.

SPECIFICATION forming part of Design No. 30,586, dated April 18, 1899.

Application filed February 1, 1899. Serial No. 704,187. Term of patent 14 years.

To all whom it may concern:

Be it known that I, EDWARD G. PARKHURST, a citizen of the United States of America, and a resident of Hartford, in the county of Hartford and State of Connecticut, have invented and produced a new and original Design for a Cartridge-Clip Receiver, of which the following is a specification.

This invention relates to a new design for a receiver for temporary cartridge-clips, and is intended to be employed in connection with the magazines of breech-loading firearms.

In the drawings constituting a part of this specification, Figure 1 is a plan view. Fig. 2 is a side view in section taken on the line 4 4 of Fig. 1. Fig. 3 is a perspective view, on an enlarged scale, looking from the front right-hand side of the receiver.

The general outline of the receiver D is substantially that of a cube having rounded corners, and having in its front face a relatively large recess open at top and bottom and forming the side wings F and G. The inner walls of each of these wings facing upon the recess are provided with the oppositely-disposed substantially vertical clip-receiving grooves H and with the inclined walls I, terminating at their lower ends in the partly-circular recess J.

The leading essential feature of this design is the configuration of the inner walls of the wings F and G, each comprising the groove H and the adjacent inclined wall I, terminating in the partly-circular recess J.

I claim—

The design for a cartridge-clip receiver, as herein shown and described.

Signed by me, at Hartford, Connecticut, this 31st day of January, 1899.

EDWARD G. PARKHURST.
